CLAIM

The ornamental design for a cap for an inhalation device, as shown and described.

DESCRIPTION

FIG. 1 is a bottom, right perspective view of a cap for an inhalation device showing my new design;

FIG. 2 is a bottom plan view thereof;

FIG. 3 is a top plan view thereof;

FIG. 4 is a left elevational view thereof;

FIG. 5 is a front elevational view thereof; and,

FIG. 6 is a rear elevational view thereof.

The broken line showing of environment in all views is for illustrative purposes only and forms no part of the claimed design.
